MANICURING APPARATUS

Vincent J. Moir, Cleveland Heights, Ohio

Application January 26, 1933, Serial No. 653,746

14 Claims. (Cl. 132—74)

This invention relates to manicuring apparatus and particularly to power operated manicuring apparatus.

In the art of manicuring the fingers and finger nails, the various operations have heretofore been performed by hand manipulation of various power operated tools or implements or toilet articles.

It is an object of this invention to provide an apparatus whereby these and other operations may be performed by power operated tools, in an improved manner.

Another object of my invention is to provide improved methods and/or means for performing various manicuring operations.

Another object is to provide an improved tool or tools for performing various manicuring operations.

Another object is to provide an improved tool or tools for effecting manicuring operations and having improved means for renewing or replacing the operative portions of the tool.

Another object is to provide an improved chuck means adapted to grip and operatively drive the manicuring tool or tools.

Another object is to provide an improved motor drive for a manicuring tool or tools.

Another object is to provide an improved portable power unit for driving manicuring tools and the like.

Another object is to provide a power operated manicuring set which will be pleasing in appearance and efficient in operation.

Another object is to provide a method and/or means whereby the necessary or desirable manicuring operations may be performed in less time than has heretofore been necessary.

Another object is to provide a method and/or means of performing manicuring operations with the minimum of discomfort to the person being operated upon.

Other objects of my invention will be apparent to those skilled in the art to which my invention appertains.

My invention is fully disclosed in the following description taken in connection with the accompanying drawings, in which:

Fig. 1 is a front elevational view of a motor power unit which I may employ and constituting a part of an embodiment of my invention;

Fig. 2 is a top plan view of the power unit of

Fig. 1;

Fig. 3 is a front elevational view of a tool set

which I may employ in the embodiment of my invention;

Fig. 4 is a longitudinal sectional view to an enlarged scale of a chuck means illustrated in Figs. 1 and 2;

Fig. 5 is a cross-sectional view taken from the plane 5—5 of Fig. 4;

Fig. 6 is an elevational view to a smaller scale illustrating the chuck means of Fig. 4 and with one form of manicuring tool which I may employ 10 assembled therewith in position for use;

Fig. 7 is a cross-sectional view to an enlarged scale of the tool illustrated in Fig. 6;

Fig. 8 is a perspective view illustrating a mode of operation of the tool of Figs. 6 and 7; 15

Fig. 9 is a cross-sectional longitudinal view of the chuck means of Fig. 4 and having assembled therewith another form of tool which I may employ;

Fig. 10 is a view similar to Fig. 7 illustrating 20 still another form of tool which I may employ;

Fig. 11 is a perspective view illustrating a mode of operation of the tool of Fig. 10;

Fig. 12 is a view similar to Figs. 7, 8 and 9 illustrating still another form of tool which I may 25 employ;

Fig. 13 is a perspective view illustrating a mode of operation of the tool of Fig. 12;

Fig. 14 is a cross-sectional view taken from the plane 14—14 of Fig. 12; 30

Fig. 15 is a sectional view taken from the plane 15—15 of Fig. 7 with parts back of the section plane omitted for clearness;

Fig. 16 is a perspective view of a part of the tool of Fig. 7. 35

Referring to the drawings, I have shown at 1 a housing preferably made of ornamental appearance and enameled in an aesthetically beautiful color and containing (not illustrated) an electric motor. Circuit wires 2 terminating 40 in a plug 3 are connected to the motor within the housing 1 for driving it in the well known manner. A switch of the tumbler type 4 controls the energizing circuit to the motor. A tubular cable housing 5 is secured to the motor housing 1 as at 6, Fig. 2, and a cable 7 within the housing is connected to a rotary part such as the armature of the motor and rotatably driven. 45

The parts thus far described form no essential part of my invention and have not been fully 50 illustrated inasmuch as electric motor driven cables of this character are well known in the art.

The cable housing 5 as shown in Fig. 4 and indicated in Fig. 2, is connected to a tool handle 55. The cable 7 is connected to a rotary part

within the handle to be described. Upon the top of the housing 1 is mounted a post 9 carrying on its upper end a U-shaped handle support 10, the legs 11 and 12 of the U being bent into C-form in generally parallel planes and with the open side of the C of the two legs facing in opposite directions. When the cable housing 5 and the cable 7 therewithin are bent or wound in the generally clockwise direction as viewed in Fig. 2 to dispose them around and upon the housing 1, the tool handle 8 may be lodged in the C-form legs 11 and 12 and the resilient tendency of the housing and cable to unwind will cause the handle to be gripped in the C-form legs 11 and 12 to secure and support it upon the housing 1, as illustrated in Figs. 1 and 2.

Furthermore, the closed end of the U-form support 10, being spaced by the post 9 from the top of the housing 1, provides a handle under which the fingers of the hand may be inserted for lifting and transporting the entire motor unit from place to place.

Referring to Fig. 4, the tool handle 8 comprises an elongated cylindrical body portion 13 to the inner end of which is secured the cable housing 5, the preferred construction comprising a sleeve 14 into which the end of the cable housing is telescoped and to which it is permanently secured, the sleeve 14 having a threaded portion 15 of reduced diameter threaded into the end of the handle body portion 13, a shoulder 16 abutting upon the end of the handle portion. Into the opposite end or outer end of the body portion of the handle, a chuck housing 17 generally of elongated cup form is screwed, by external threads 18 on the chuck housing and corresponding inner threads on the body portion of the handle, and the inner end of the chuck housing may abut upon a shoulder of the body portion, as for example at 19, to rigidly secure these parts together.

The outer end or cup bottom of the cup-form chuck housing is provided with a perforation or aperture 20 through which the shank portions 45 of tools may be inserted in a manner and for a purpose to be described.

The end of the chuck housing 17 is preferably formed cylindrical as at 21 and provided with a shoulder 22.

Within the tool handle 8 is a rotatably mounted shaft 23 the outer end of which terminates, as at 24, adjacent the end of the chuck housing 17 and is longitudinally bored as at 24' in alignment with the aperture 20 and longitudinally slotted as at 25 to provide a plurality of resilient chuck jaws 26-26 for gripping a tool shank to be described, and the outer surfaces of the jaws are tapered, flaring outwardly toward the outer end as shown at 27. A chuck jaw operating sleeve 28 slidably mounted on the shaft 23 engages at its outer end portion as at 29 the tapering portion of the jaws. By this construction when the sleeve 28 is moved outwardly, the jaws are moved radially inwardly to grip a tool shank therewithin; and when the sleeve is moved in the opposite direction the resilience of the jaws moves them outwardly to release the tool shank.

The movement to engage the tool shank is effected by a compression spring 30 surrounding a portion of the shaft 23, abutting at its inner end upon a flange 31 of a sleeve 32 telescoped over the shaft and preferably secured rigidly thereto by a pin 33 projected through the sleeve 32 and the shaft; and the other end of the spring 75 abutting upon the inner end 34 of the chuck oper-

ating sleeve 28; and to move the sleeve 28 in the chuck-releasing direction, the following construction is provided.

An external sleeve 35 is mounted to slide on the body portion 13 and chuck housing 17, being telescoped thereover, and has threaded therein a plurality such as three radially extending screws 36-36, the screws having smooth unthreaded cylindrical inner end portions 37 projecting through longitudinally extending slots 38 in the tubular wall of the chuck housing 17 and projecting at their inner ends into an annular groove 38' in the outer surface of the sleeve 28.

By slidingly moving the sleeve 35 inwardly, the ends 37 of the screws 36 engage the side of the groove 38 and retract the sleeve 28 against the compression of the spring 30 to release the chuck jaws and upon releasing the sleeve 35, it, together with the sleeve 28, are returned by the spring 30 to the chuck gripping position illustrated.

The flange 31 prevents axial movement of the shaft 23 inwardly and movement of the shaft outwardly is prevented or stopped by a flange 39 on a connecting element 40 threaded upon a reduced end 41 of the shaft. The flanges 31 and 39 may abut upon corresponding opposite shoulders 42 and 43 formed in the body portion 13 of the tool handle 8.

The connecting element 40 comprises a generally cylindrical portion 42' into which the threaded portion 41 of the shaft is screwed at one end and at the opposite end is bored out as at 43 and has rigidly secured therein the end of the driving cable 7, as shown in Fig. 4, the outer diameter of the element 40 being sufficiently small to rotate freely in the bushings 14-15.

By the construction above described it will now be clear that the tool handle may be grasped by an operator by the body portion 13 and chuck housing 17 and sleeve 35, these portions remaining stationary and not rotating; and that upon application of power to the motor above referred to to rotate the cable 7, the shaft 23 together with the chuck jaws 26 thereof will be rotated in the handle and a tool whose shank is projected through the aperture 20 and gripped by the chuck jaws and projecting outwardly from the end of the handle will likewise be rotated. Furthermore, the tool shank may be inserted in chuck jaws or removed therefrom while the chuck 50 is being rotated, that is to say, without stopping the motor.

Tools operable by the chuck handle just described will now be considered in connection with various manicuring operations which may be 55 performed.

A nail polishing operation may be performed by the tool illustrated in Fig. 9, the tool being illustrated in connection with a portion of the chuck handle above described. The tool comprises a holder 45 having a cylindrical sleeve portion 46 adapted to slide over the outer end portion 21 of the tool handle above described. Outwardly the holder 45 has a cylindrical bore 47 therethrough in which is rotatably mounted 60 a tool shaft 48 having a collar 49, preferably formed integrally therewith, engageable with an interior shoulder 50 of the holder to prevent axial movement of the shaft in the holder in one direction, the shaft 48 beyond the shoulder 49 being reduced in diameter to provide a shank 51 65 adapted to be inserted through the aperture 20 and within the chuck jaws 26 above described and to be gripped by the same.

The outer end of the shaft 48 has a reduced 75

threaded portion 52 upon which is screwed a sleeve-like extension 53 of substantially the same outside diameter as the shaft 48 in the bore 42; and the sleeve 53 has joined to its outer end a 5 cup-form receptacle 54. A tapering screw 55 projects axially into the cup-form receptacle 54, the screw being secured to the outer end of the threaded portion 52 of the shaft, for example by a nut portion 56 of the screw press-fitted into 10 a recess in the end of the portion 52.

A polisher or buffer 57 having an axial bore 58 therethrough is mounted in the receptacle 54 and is of a size to substantially fit the inner wall thereof and with the screw 55 screwed into 15 the bore 58. The buffer 57 is made from suitable buffering material such as felt or like material.

In operation of the tool of Fig. 9, the motor turns the chuck jaws in the manner above described and thereby turns the shank 51 and shaft 48 and the buffer 57 at relatively high 20 velocity. The end portion 59 or side portion 60 of the buffer 57 may be applied to the finger nail to polish the same with a buffering action. In presenting the buffer to the finger nail, the hand 25 of the operator may embrace the handle above described and may support the buffer by gripping the holder 45 within which the shaft 48 rotates as will now be understood. The holder 45 is maintained in assembled relation with the shaft 48 partly by engagement of the collar 49 with the shoulder 50 as described and also by the engagement of the outer end 61 of the holder with a shoulder portion 62 of the receptacle 54.

As will be apparent, the buffer 57 may be readily 25 removed and renewed or replaced. To secure the buffering tool to the handle, it is only necessary to slide the sleeve 35 inwardly, insert the shank 51 in the chuck and the sleeve portion 46 of the holder over the end of the tool and release the sleeve 35 as will be understood from the foregoing description.

Due to the circular shape of the end of the cylindrical buffer 57, all portions of the nail to the extreme edges thereof may be reached to 45 be buffed and polished and the buffer may have applied thereto polishing material as will be understood by those skilled in this art. The ease of mounting a buffer 57 in the tool and of removing it therefrom and the relatively small 50 expense of the buffer due to the simplicity of its construction, permits the use of a fresh buffer for each manicuring operation for sanitary and like purposes.

In Figs. 10 and 11 is illustrated a nail cleaning tool and a method of operation thereof. The tool as shown in Fig. 10 comprises a holder 63 generally similar to the holder 45 above described having an axial bore 64 in which is rotatably mounted a shaft 65 having a collar 66 60 abutting against an internal shoulder 67 of the holder and an outer shoulder 68 abutting against the outer end of the holder. The shaft 65 is preferably formed from two pieces 69 and 70 telescopically threaded together; a chuck jaw 65 engaging shank 71 extending inwardly from the piece 69. Both pieces 69 and 70 are axially bored as at 72 to receive the stem 73 of the nail cleaning tool, the inner end of the stem being threaded as at 74 into the shaft piece 69.

The outer end of the stem 73 has mounted thereon a plurality of bristles 75, the outer ends of which are disposed in a plane 76 at right angles to the rotary axis; and inwardly of their ends, the bristles 75 are disposed to define a frustum 75 of a cone, and inwardly, toward the apex of

the cone, the bristles are clamped as at 77 between a pair of frusto-conical outer and inner sheet metal stamping elements 78 and 79. Preferably the outer element 78 has a tubular extension 80 surrounding the stem 73 and abutting inwardly upon a shoulder 81 thereof. The stem, outwardly of the shoulder, extends through the tubular portion 80, and through a suitable perforation in the inner clamping element 79 and is riveted over as at 82 exerting a clamping and 10 supporting action on the bristles.

Upon mounting the tool of Fig. 10 upon the handle by inserting the shank 71 in the chuck jaws, the bristles 75 may be rapidly rotated and may be presented to the finger to be cleaned by 15 grasping the tool handle and the tool holder 63, the latter not rotating as will now be understood, and as illustrated in Fig. 11. The bristles may be presented to the nails to clean any desired portion thereof on the outer or on the under- 20 side thereof and by virtue of disposing the holder 63 adjacent the rotating bristles, their position may be delicately controlled to avoid directing the bristles against sensitive portions of the flesh such as that under the nails, or at the cuticle. 25

Inasmuch as the stem 73 is removable from the tool together with the bristles thereon, the same may be readily disinfected if desired.

In Figs. 6, 7, 8, 15 and 16 is illustrated a tool 30 for trimming the finger nails.

As shown in Fig. 7, the tool comprises a holder 85 comprising a sleeve portion 86 for telescoping over the end of the tool handle and a shank 87 to be gripped by the chuck. A head 88 has a cylindrical bearing stem portion 89 telescoped into a corresponding bore 90 of the holder 85 and is rotatable therein. The head has a flange of increased diameter 91 outwardly thereon in the outer end of which is formed an oblong recess 35 92. The periphery of the flange 91 is preferably frusto-conical in form diverging outwardly and is substantially surrounded by a skirt 93 on the holder 85, internally frusto-conical to substantially fit with small clearance the flange 91. The 40 edge 94 of the skirt projects beyond the outer end of the flange 91. The shank 87 on the end opposite the chucking portion thereof is enlarged to provide a head 95 terminating outwardly in an enlarged flange 96. A sand paper or emery 45 disc 97 having a perforation 98 therein substantially the same size and shape as the head 95 is disposed between the flange 91 and the flange 96.

The shank 87 may be inserted into the chuck jaws and with the end of the handle as at 99 disposed adjacent the inner end of the head 89. Rotation of the shank 87 will rotatably drive the head 91 and the disc 97. The disc may be readily renewed by removing the shank from the chuck jaws as will be understood from the foregoing 55 description and from the drawings.

When the tool as shown in Fig. 7 is secured to the handle as described, the holder 85 may be grasped by the hand as illustrated in Fig. 8 to effect delicate control of the position of the disc 65 97 and the disc may be presented to the fingers to trim and shape the same as desired. The overlapping skirt 93 permits it to rest against the flesh adjacent the nail edge so as to avoid any possibility that the rotating emery disc may 70 contact with the flesh, and to further assist the operator in directing the movement and position of the disc.

Preferably a slot or recess 100 is provided in the skirt 93 extending part way therearound and 75

on a portion which may be disposed remote from the finger being operated upon to facilitate the removal, by centrifugal force, of dust and the particles of emery which are freed from the finger nail and from the trimming disc during the operation thereof and to prevent the same from working inwardly to the bearing surface 90.

In Figs. 12, 13 and 14 is shown a tool for treating the cuticle at the base of the finger nail by compressing or compacting the same toward the base of the nail. The tool comprises a holder 102 generally of sleeve form adapted to be telescoped over the end of the tool handle and having screw-threadedly telescoped into its outer end a guide 103 tapering outwardly and having an axial bore 105 therein. The chuck jaw engageable shank 106 is provided with a collar 107 disposed against the inner side of a flange 108 and forwardly of the collar projects through a perforation 109 in the flange and terminates in a threaded portion 110.

A cam 111 is rigidly threaded upon the threaded portion 110 and is generally of hollow cylindrical form, the outer end of which is provided with a camming surface 112.

A sleeve 113 is disposed in the bore 105 above referred to and on its inner end has an enlargement 114 of hollow cylindrical form provided on its inner end with a cam surface 115. A pin 116 is projected through the cam 114 and opposite ends are disposed in axially extending parallel slots 117—117 in a tubular extension 118 of the head 103, and within which tubular extension the cams 112 and 114 are disposed. A compression spring 118' abuts at one end upon a shoulder 119 of the sleeve 113 and upon a shoulder 120 of the guide 103 whereby the sleeve 113 and its cam 114 is resiliently thrust inwardly to maintain the cam faces in engagement.

In the outer end of the sleeve 113, a tool tip 121 is telescopically inserted terminating outwardly in a preferably wedge-shaped end 122. The tip 121 may be formed from any suitable material but orangewood or the like is preferred.

By the foregoing construction as will now appear, when the shank 106 is gripped by the chuck and is rotated, rotating the cam 111, its cam face reacting on the cam face 115 of the cam 114 will transmit thereto a reciprocating movement, one complete reciprocation for each revolution, and giving to the tool tip at 122 a rapid reciprocatory movement. The holder 102 is unmoved during this operation and the tool handle may be gripped by the operator's hand, and with the holder 102 between his fingers as illustrated in Fig. 13, and the tip 122 may be applied to the cuticle at the base of the nails to compress and compact the same for the well known purposes.

The tool tip 121 may be readily removed for renewal for sanitary purposes or the like.

As will now be apparent from the above description, I have provided by my invention, not only improved apparatus by which manicuring operations may be performed, but apparatus performing these operations in an improved manner. The various tools are constructed to facilitate the performance of the various operations by the manicurist, and the operations are performed without discomfort or danger to the fingers being manicured; and the tools for the various operations may be mounted in a common handle for power drives by simple movements or removed therefrom without the necessity of acquiring skill; and the portions of the tools coming in contact with the fingers being operated upon may be

renewed or disinfected for sanitary purposes or the like; and the apparatus is adapted for use by a professional manicurist or by the user himself upon his own fingers. All of the necessary operations are performable by the apparatus above described and therefore a complete manicuring operation may be effected in the minimum of time.

The tool case of Fig. 3 preferably comprises a base 125 supporting a rotatable head 126 having spaced vertically disposed bores 127 therein in which the shanks 51, 71, 87 and 106 of the several tools may be inserted when not in use and from which they may easily be reached and removed for mounting in the tool handle 8. A cover 128 having a handle 129 is provided for the tool supporting base to cover the tools when not in use.

Thus by constructing the motor housing 1 of Figs. 1 and 2 and the tool case of Fig. 3 to have ornamental aesthetic appearance, the entire outfit may be made aesthetically beautiful to harmonize with decorations of professional manicuring establishments or to suit the personal taste of individual purchasers and users for installation in the home.

My invention is not limited to the exact details of construction shown and described. Many changes and modifications may be made within the scope and spirit of the invention without sacrificing its advantages.

I claim:

1. In a manicuring apparatus, a tool holder comprising a handle having a generally cylindrical end portion and a coaxial rotatable chuck therein, a tubular tool support comprising a holder, a sleeve extension on the holder adapted to be telescoped over the cylindrical portion of the handle, a spindle rotatably supported in the holder and having a shank portion adapted to be inserted into the chuck simultaneously with the said telescopic movement of the sleeve onto the handle end, means to prevent axial shifting of the spindle in the holder, and a rotary manicuring tool element on the outermost end of the spindle opposite the shank.

2. In a manicuring tool, a tubular support, a head rotatably mounted in the support and having a transverse face and a substantially coaxial oblong recess in the face and an abrasive disc on the face provided with a substantially coaxial oblong perforation, a spindle having a flat head engaging the abrasive disc face, a neck of oblong cross-section under the head in the oblong perforation and oblong recess and having a chuck engaging shank portion extending through and out of the head.

3. A manicuring tool as described in claim 2 and in which the head is removable axially outwardly from the holder and the spindle is removable axially outwardly from the head and the disc.

4. In a manicuring tool holder, an elongated hollow handle member rotatively supporting a spindle therein adapted to be connected to a rotary power cable, an end of the spindle having a tool gripping chuck associated therewith, the spindle being held against axial movement relative to the hollow handle member, a manually operable chuck control member disposed at the handle surface and non-rotatably associated therewith, a collar positioned in said hollow handle member and surrounding said spindle and rotatable therewith, and movable axially thereof by the chuck control member to actuate the chuck.

5. In a manicuring tool holder, an elongated

- hollow handle member rotatively supporting a spindle therein adapted to be connected to a rotary power cable, an end of the spindle having resilient radially movable portions forming a tool gripping chuck, the spindle being held against axial movement relative to the hollow handle member, a collar positioned in said hollow handle member and surrounding said spindle and rotatable therewith, and movable axially thereof to control the chuck, and a spring normally moving said collar to the chuck gripping position.

6. In a manicuring tool holder adapted to grip the tool by a rearwardly extending shank portion, an elongated hollow handle member rotatively supporting a spindle therein adapted to be connected to a rotary power cable, an end of the spindle having a tool gripping chuck associated therewith, the spindle being held against axial movement relative to the hollow handle member, a collar positioned in said hollow handle member and surrounding said spindle and rotatable therewith, and movable axially thereof to control the chuck, and a manually operable non-rotatable member positioned exteriorly of the hollow handle and operable to move said collar to the chuck released position.

7. In a manicuring tool holder adapted to grip the tool by a rearwardly extending shank portion, an elongated hollow handle member rotatively supporting a spindle therein adapted to be connected to a rotary power cable, an end of the spindle having a tool gripping chuck associated therewith, the spindle being held against axial movement relative to the hollow handle member, a collar positioned in said hollow handle member and surrounding said spindle and rotatable therewith, and movable axially thereof to control the chuck, a spring normally urging said collar to the chuck gripping position, and a manually operable non-rotatable member positioned exteriorly of the hollow handle and operable to move said collar to the chuck released position.

8. In a device of the class described, a tool holder comprising a handle having a generally cylindrical portion adjacent one end, and a coaxial rotatable chuck mounted therein, a tool support comprising a member having a cylindrical portion adapted to be telescoped with the cylindrical portion of the handle, a spindle rotatively supported in said member and having at one end a generally cylindrical shank portion adapted to be gripped by the tool holder chuck and to be rotated thereby and adapted to receive a manicuring tool at its outermost end.

9. In a device of the class described, a tool holder comprising a handle having a generally cylindrical portion adjacent one end, and a coaxial rotatable chuck mounted therein, a tool support comprising a member having a cylindrical portion adapted to be telescoped with the cylindrical portion of the handle, a spindle rotatively supported in said member and having at one end a shank portion adapted to be gripped by the tool holder chuck and to be rotated thereby, the tool support and the spindle being so formed as to prevent relative longitudinal movement.

10. In a device of the class described, a tool holder comprising a handle having a generally cylindrical portion adjacent one end, and a coaxial rotatable chuck mounted therein, a tool support comprising a member having a cylindrical portion adapted to be telescoped with the cylindrical portion of the handle, a spindle rotatively supported in said member and having at one end a shank portion adapted to be gripped by the tool holder chuck and to be rotated thereby, and having at the other end a receptacle adapted to secure a tool element by a rearwardly extending portion thereof.

11. In a device of the class described, a tool holder comprising a handle having a generally cylindrical portion adjacent one end, and a coaxial rotatable chuck mounted therein, a tool support comprising a member having a cylindrical portion adapted to be telescoped with the cylindrical portion of the handle, a spindle rotatively supported in said member and having at one end a shank portion adapted to be gripped by the tool holder chuck and to be rotated thereby, and having at the other end a cup-form receptacle having a coaxial screw-threaded extension adapted to secure a buffering element by a rearwardly extending portion thereof.

12. In a device of the class described, a tool holder comprising a handle having a generally cylindrical portion adjacent one end, and a coaxial rotatable chuck mounted therein, a tool support comprising a member having a cylindrical portion adapted to be telescoped with the cylindrical portion of the handle, a spindle rotatively supported in said member and having at one end a generally cylindrical shank portion adapted to be gripped by the tool holder chuck and to be rotated thereby, and having at the other end a threaded bore adapted to receive a tool element having a threaded shank.

13. In a device of the class described, a tool holder adapted to be employed with a handle having a chuck rotatively mounted therein, said tool holder comprising a member having a spindle rotatively supported therein, and means preventing longitudinal movement of the spindle in the member, the spindle having adjacent one end a generally cylindrical shank adapted to be engaged by the chuck, and having adjacent the other end a portion adapted to receive a tool element.

14. In a device of the class described, a tool holder adapted to be employed with a handle having a chuck rotatively mounted therein, and having adjacent one end a substantially cylindrical portion, said tool holder comprising a member having a cylindrical portion adapted to be telescoped with the cylindrical portion of the handle, said member having a spindle rotatively mounted therein, and means preventing longitudinal movement of the spindle in the member, the spindle having adjacent one end a generally cylindrical shank adapted to be engaged by the chuck, and having adjacent the other end a portion adapted to receive a tool element.

VINCENT J. MOIR
